INFANT RESUSCITATOR

Vivian Ray Bennett, Beverly Hills, Calif.

Application March 7, 1955, Serial No. 34,898

Term of patent 14 years

(Cl. D83—1)

Fig - 1

Fig - 2

Fig - 3

I claim:

The ornamental design for an infant resuscitator, substantially as shown.
